UNITED STATES PATENT OFFICE.

VICTOR H. BUSCHMANN, OF BALTIMORE, MARYLAND, ASSIGNOR OF ONE-HALF TO AUGUSTUS H. BRINKMANN, OF SAME PLACE.

BUSTLE.

SPECIFICATION forming part of Letters Patent No. 358,800, dated March 1, 1887.

Application filed July 9, 1886. Serial No. 207,569. (No model.)

To all whom it may concern:

Be it known that I, VICTOR H. BUSCHMANN, a citizen of the United States, residing at Baltimore city, State of Maryland, have invented 5 new and useful Improvements in Bustles, of which the following is a specification.

I have improved the style of bustle in which the contour is formed by a series of spring-wire bows arranged in overlying relation to 10 each other, each one below the other increasing in length and extending to a connection with the waistband.

My improvement consists in combining with 15 spring-bows, arranged as stated, two or more transverse spring-stays composed of a series of arches arranged one above the other within the contour of bows and connected with the latter and with the waistband. These series of spring-arches I prefer to make of a single 20 wire strand, one end of which connects with the series of bows and the other end with the waistband, and the arches are formed between these end parts, one above the other, and attached to and supported upon said end parts 25 in such manner that the bows and arches may yield in every direction and retain the form of contour for sustaining the skirts.

In the drawings, Figure 1 represents my 30 improved bustle in perspective; Fig. 2, a vertical cross-section; and Figs. 3 and 4 show the series of spring-arches formed of a single-strand-wire tape.

The bows *a*, which form the contour of the bustle, are connected to the waistband *b* by 35 pockets *c*, to which their ends are secured by eyelets or otherwise. These bows are of tape-wire, and increase in length from the top to the bottom, so as to give a convex contour extending sufficiently down and out from the 40 waist. To support the bows and maintain the proper contour, I provide two or more spring-arched frames placed transverse between the ends of the bows, each composed of two or more arches, *d*, standing vertically 45 and increasing in span from the top to the bottom. These several arches stand out from the waistband and extend therefrom at different heights from the upper to the lower bow, to which they are connected, while at their 50 inner ends they connect with the waistband by hangers.

I prefer to form each arch-frame of a single piece of tape-wire, as shown, in which the upper arch extends from the top bow down to the lowest bow and forms the smallest top 55 arch and the widest span, while intermediate arches are formed by continuous bends. One end of this arched frame is connected at *e* to the waistband *b*, and extends down and forms a back hanger, *f*, and the lowest arch, 60 which is secured by clasps *g* to the lower bow. The upper arch is projected from the lower one, and is connected with and supported by the back hanger, along which it extends to the bottom arch and terminates in an interior 65 arch supported upon the back hanger and upon the outer arch, to which it is fastened by the clasp *g*, thus forming a multiple of arches from a single strand of spring-wire, having one end fastened to the waistband and 70 the other end fastened to the outside arch at the lower bow. Where the strands join each other in forming the arches they are secured together by clamps. These frames or arches are connected together by a stay, *h*, at the 75 lower ends of the hangers; and the bustle-frame so constructed can yield in any direction upon the hangers upon which the spring-arches exert their force outward and upward, while permitting the latter to bend down with 80 the bows, to bend inward with the bows, and to bend sidewise with the bows.

The arches of the spring-frame are bound together, with one end, *f*, of the wire projecting up from the hanger, for attachment to the 85 waistband, as in Figs. 3 and 4.

I claim—

The bustle herein described, provided with supporting springs and spring-bows, said supporting-springs comprising a series of upwardly-arched spans, an upper one, a lower one, and an intermediate one, bound together and to the bows, as shown, and forming a hanger for attachment to the bustle-waistband. 90

In testimony whereof I have hereunto set my hand in the presence of two subscribing witnesses.

VICTOR H. BUSCHMANN.
